UNITED STATES PATENT OFFICE

2,635,639

HYDRAULIC REGULATOR WITH
STABILIZING DEVICEMarkus A. Eggenberger, Schenectady, N. Y., as
signor to General Electric Company, a corpora-
tion of New York

Application October 17, 1951, Serial No. 251,696

3 Claims. (Cl. 137—781)

1

This invention relates to hydraulic servo-mechanism, particularly to a hydraulic-mechanical device for overcoming inherent instability in a hydraulic regulator used to control the steam supply to the shaft packing seal of a steam turbine type of prime mover. This regulation job is made difficult because the volume in the piping between the seal and the regulator is small, and rapid response of the regulator is desired.

As will be appreciated by those skilled in the art relating to hydraulic servo-mechanisms, the tendency of a servo to become unstable and "hunt" becomes greater as the "regulation" of the mechanism approaches zero, "regulation" being the change occurring in the condition being sensed as the condition being governed changes from its minimum value to its maximum value. Many expedients have been employed by the prior art to achieve stability when the regulation of the hydraulic servo equals or approaches zero, or becomes negative. One such expedient is a liquid-filled dashpot, variously arranged to introduce a frequency sensitive phase lag effect for damping the tendency to become unstable. Such dashpot arrangements are shown for instance in the patent to Dettenborn—2,077,384, issued April 20, 1937, and Warren—2,113,416, issued April 5, 1938, both assigned to the same assignee as the present application. In some places, such dashpot devices have not been completely satisfactory, partly due to the fact that there is inherently a certain amount of friction in the dashpot.

Accordingly, an object of the present invention is to provide an improved hydraulic-mechanical stabilizing device for servo-mechanisms of the type described in which mechanical friction has been eliminated.

Another object is to provide a hydraulic servo stabilizing device which, in the event of a sudden change in the condition being sensed, will provide, instantaneously, a degree of regulation many times that which is effected when the condition change takes place more slowly.

Other objects and advantages will become apparent from the following description taken in connection with the accompanying drawing, in which the single figure represents diagrammatically hydraulic servo-mechanism having a stabilizing device incorporating the invention.

Generally, the invention is practiced by providing an expansible liquid-filled chamber associated with the condition-responsive member in such a way that movement of the member in accordance with changes in the condition causes an interchange of liquid with a hydraulic stabilizing

2

device arranged in accordance with the invention.

Referring now more particularly to the drawing which shows schematically a hydraulic regulating system partly in section, a hydraulic regulator indicated generally at 1 is arranged to receive high pressure steam from a boiler 2 and supply it at a much lower pre-selected pressure to a shaft seal 3a of a steam turbine indicated generally at 3.

The pressure regulator 1 is of a type previously known, and the mechanical details thereof are not material to an understanding of the present invention. It need only be noted that a signal output rod member 4 is positioned by a condition-responsive device 5 to control pilot valve 6 of hydraulic motor 7 so as to actuate a dual steam regulating valve which admits steam through valve 8 from boiler 2 or, alternatively, dumps steam to the condenser 3b by opening valve 9.

This invention particularly relates to the hydraulic stabilizing device 10 for modifying the forces applied to the condition-responsive signal output member 4 in order to achieve stability.

As shown in the drawing, the condition-responsive device 5 comprises a housing 11 defining a pressure chamber 12 to which is communicated by conduit 13 the pressure of the steam supplied to turbine shaft seal 3a by hydraulic servo 1. The housing 11 may conveniently be fabricated with an end closure member 11a and a bushing member 11b which has a central bore defining a generous annular clearance space, shown at 14, with the output rod member 4.

The output rod 4 is biased downwardly by a spring 4a, and the lower end of the rod carries a first disk member 15 the lower surface of which is subjected to the input signal pressure in chamber 12. To the outer circumference of disk 15 is sealed a flexible bellows member 16 cooperating with an inner bellows member 18 to define a first annular expansible chamber 17. The upper ends of bellows 16, 18 are sealed to the end closure member 11a.

The annular chamber 17 is filled with a hydraulic liquid, such as a suitable petroleum oil, which liquid is communicated by way of conduits 19, 20, 21, with the hydraulic stabilizer 10. It will be seen that, since the space within bellows 18 communicates with the atmosphere by way of the generous clearance space 14, the disk 15 is positioned against the bias of spring 4a by steam pressure in chamber 12 acting on an annular area of the disk, as may be modified by liquid pressure in chamber 17.

The hydraulic stabilizing device 10 comprises a

housing 10a which may conveniently have end closure members 10b, 10c. Within the housing is a second abutment disk member 22 which "floats," free of frictional contact with housing 10, between two opposed coil springs 23, 24. The lower surface of disk 22 is sealed to a flexible bellows 25 which defines a second expansible chamber 26, bellows 25 having its lower end sealed to the lower end closure 10b.

For indicating the position of disk 22, a rod 23 secured to disk 22 may project through the upper end closure 10c, defining a generous annular clearance space 27 therewith. As will be apparent in the drawing, conduit 20 freely communicates liquid from annular chamber 17 to chamber 26 in the stabilizer 10, while conduit 21 communicates liquid to the space 28 above disk 22 and surrounding bellows 25. The space 28 serves as a storage reservoir for liquid displaced from chamber 17, and also serves to keep the connecting conduits full of liquid at all times. To this end, the conduit 21 is connected to housing 10a at a location below the lowest normal level of oil in space 28.

It remains to be noted that conduit 21 includes a throttling valve 21a, or equivalent flow restricting device, for a purpose indicated by the method of operation described hereinafter.

To appreciate the operation of stabilizer 10, assume first that the throttling valve 21a is wide open. If now the steam pressure communicated to chamber 12 by conduit 13 should suddenly increase, the pressure responsive disk 15 will move upwardly against the downward force of spring 4a, substantially unaffected by the liquid in chamber 17, which liquid is merely displaced through conduit 19, 21 to the generously proportioned reservoir space 28 above disk 22 and around bellows 25. In this connection, it should be noted that chamber 28 is in free communication with the atmosphere by way of the clearance space 27, and with the space surrounding bellows 25 by way of the generous clearance space 22b defined between disk 22 and housing wall 10a. Thus, except for a comparatively small amount of hydraulic damping effected by the flow of liquid from chamber 17 to chamber 28, the operation of the servo-mechanism I will be in the manner of the prior art devices of this type. This means that the inherent degree of "regulation" will be determined by the mechanical characteristics of the spring 4a. For instance, this spring may be so selected that the servo-mechanism I will control the shaft sealing steam pressure with a change of perhaps 1 pound per square inch as the rate of steam flow changes from maximum to minimum.

This degree of regulation may be insufficient to insure stability of the system; therefore, the stabilizer 10 is brought into action. To this end, the throttling valve 21a is closed partially. If now a sudden increase in the steam pressure occurs, any tendency for disk 15 to move upwardly is resisted, by liquid pressure produced in chamber 17, resulting from the flow of liquid from chamber 15 through conduit 19, 20 to the expansible chamber 26, which moves disk 22 upwardly against the force of spring 23. Conversely a sudden decrease of pressure in chamber 12 will cause liquid to be drawn from chamber 26 so as to move disk 22 downwardly against the bias of spring 24. Thus springs 23, 24 introduce an extraneous force which is transmitted hydraulically to disk 15 when it tries to move suddenly. The effect of this action is to greatly in-

crease the degree of regulation introduced into the operation of servo-mechanism I. For instance, as compared with a normal regulation of about 1 pound, when valve 21a is wide open or when the pressure changes occur slowly, the instantaneous degree of regulation effected when valve 21a is partly closed may be 10 pounds per square inch or more. The magnitude of this instantaneous regulation is determined by proper selection of the springs 23, 24, just as the normal regulation of the system is determined by the mechanical characteristics of spring 4a.

The effect of varying the resistance to flow through conduit 21, by changing the degree of opening of valve 21a, is to alter the length of time required for the regulation of the system to change from the high "instantaneous" value to the lower "steady state" value. With this valve wide open, the regulation quickly settles down to the "steady state" value. With the valve completely closed, it takes an infinite length of time.

In other words, the stabilizer 10 effects its stabilizing function by providing an instantaneous degree of regulation, in the event of a sudden change in the condition being controlled, which is many times greater than the "steady state regulation" which takes place with more gradual changes in the condition. Specifically, the stabilizer may be designed and adjusted to provide an instantaneous degree of regulation on the order of 10 pounds in the event of sudden large changes in steam pressure, the degree of regulation being gradually reduced to a normal value on the order of 1 pound after a time interval determined by the adjustment of valve 21a.

It will be seen that this stabilizing effect is produced without interference from any mechanical friction effects, since the movable disks 15, 22 and the rods 4, 23 have no frictional engagement with the associated housing portions. Thus the invention provides a very simple, yet readily adaptable means for stabilizing a hydraulic servo-mechanism without the interference of mechanical friction effects.

It will be understood that, while the invention has been described as applied to a steam regulator for the shaft seal of a turbine, it may be applicable to many other types of servo-mechanisms where analogous problems are encountered. It is also to be noted that the specific mechanical details disclosed herein are intended to be only in the nature of a diagrammatic representation of the mechanical components required to practice the invention; and it will be obvious to those skilled in the art that the mechanical parts may take many alternate forms. It is, of course, intended to cover by the appended claims all such modifications as fall within the true spirit and scope of the invention.

What I claim as new and desire to secure by Letters Patent of the United States is:

1. In a servo-mechanism, the combination of a signal output member adapted to be positioned linearly by a signal input force, a first disk member secured to the output member and walls defining therewith a first expansible chamber, and a hydraulic stabilizer comprising walls defining a second chamber vented to the atmosphere and forming a reservoir partly filled with liquid, a second disk member disposed in the second chamber, first and second spring means disposed in the second chamber at opposite sides of said second disk to establish a neutral position therefor, walls defining a second expansible chamber connected to one side of the second disk, first con-

duit means communicating liquid freely between the interior of the first and second expandible chambers, and second conduit means communicating with the first expandible chamber and connected to the second stabilizer chamber at a location below the lowest normal level of the liquid therein, and flow restricting means in said second conduit, whereby movement of the signal output member causes displacement of liquid between the first expandible chamber and the stabilizer, the flow through said first and second conduits being different by reason of the flow restriction in the second conduit so that sudden movement of the output member results in movement of the second disk member against the bias of one stabilizing spring to create a liquid pressure in the first expandible chamber tending to resist such movement of the output member.

2. In a servo-mechanism, the combination of a signal output member adapted to be positioned by a signal input force, a first disk member connected to the output member and walls defining therewith a first expandible chamber, and a hydraulic stabilizer comprising walls defining a second chamber vented to the atmosphere and forming a reservoir partly filled with liquid, a second disk member disposed in said second chamber, first and second opposed spring means disposed in said second chamber and acting on the second disk to establish a neutral position therefor, walls defining a second expandible chamber adapted to exert force on one side of the second disk, conduit means communicating liquid between said first and second expandible chambers and said reservoir, said conduit means communicating with the reservoir at a location below the lowest normal liquid level therein and having means restricting the flow of liquid to the reservoir, whereby movement of the signal output member effects free interchange of liquid between the first and second expandible chambers and past said flow restriction to the reservoir so that sudden movement of the output member effects movement of the second disk member against the bias of said spring means to create a liquid pres-

sure in the first expandible chamber tending to resist such movement of the output member.

3. In a servo-mechanism, the combination of an output member adapted to be positioned by a signal input force, a first abutment member connected to exert a force on the output member and walls defining therewith a first expandible chamber, and hydraulic stabilizer means comprising walls defining a second chamber vented to the atmosphere and forming a reservoir partly filled with liquid, a second abutment member disposed in the second chamber with first and second opposed spring means acting on said second member to establish a neutral position therefor, walls defining a second expandible chamber connected to exert force on said second member, conduit means communicating liquid between said first and second expandible chambers with a branch to said reservoir, said branch conduit communicating with the reservoir at a location below the lowest normal liquid level therein and having means restricting the flow of liquid to and from the reservoir, whereby movement of the output member effects free interchange of liquid between the first and second expandible chambers and limited flow past said flow restriction to the reservoir so that sudden movement of the output member causes the second abutment member to move against the bias of the opposed spring means to create a liquid pressure in the first expandible chamber tending to resist such movement of the output member.
